UNITED STATES PATENT OFFICE.

WILLIAM MATT HEUN, OF HASTINGS, NEBRASKA.

LADDER BRACKET.

Application filed September 4, 1923. Serial No. 860,816.

To all whom it may concern:

Be it known that I, WILLIAM M. HEUN, a citizen of the United States, residing at Hastings, in the county of Adams and State 5 of Nebraska, have invented a new and useful Ladder Bracket, of which the following is a specification.

This invention aims to provide an attachment which will enable a ladder to be 10 used in many places, conveniently, wherein, in the absence of the attachment, the ladder could not be used advantageously, the device, generally stated being in the nature of a prop, adapted to hold the ladder away 15 from a building.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:

Figure 1 shows in top plan, a device constructed in accordance with the invention, a portion of the ladder appearing in section; Figure 2 is a side elevation showing the 35 device forming the subject matter of this application assembled with a ladder; and Figures 3 and 4 are diagrammatic views illustrating some of the uses to which the device claimed may be put.

40 In the drawings, the numeral 1 indicates the stile of a ladder, one of the rungs of the ladder appearing at 2. On each stile 1 is mounted a prop which will now be described in detail.

45 The prop comprises a main member 3, in the form of a bar, provided at its inner end with an extension 4 disposed at right angles to the bar 3, the extension carrying an inwardly projecting hook-shaped jaw 5, 50 disposed approximately parallel to the main member or bar 3. An L-shaped jaw 6 is provided and includes an extension 7, connected by securing elements 8 to the main member or bar 3, the jaws 5 and 6 projecting toward each other, in opposite directions,

and being spaced apart transversely, the construction being such that when the opposite edges of the stile 1 are engaged by the jaws 5 and 6 as shown in Figure 1, the main member 3 of the prop will stand at 60 right angles to the stile 1. Clamping devices 9, such as screws, may be mounted movably in the parts 6 and 5, and are adapted to engage the stile 1, as shown in Figure 1 to hold the prop thereon. The main member 3 of the prop comprises an outwardly extended and laterally inclined arm 10. An extension 11 may be used, the same being pointed at its working end, as shown at 12, the extension having loop-shaped guides 14 70 wherein the arm 10 is received. A securing device 15, such as a screw, connects the extension 11 detachably with the arm 10 of the prop. The arm 10 and the extension 11 are laterally and outwardly inclined as 75 shown in Figure 1, the points 12 are spaced apart by a distance greater than the width of the ladder, and consequently, a firm support for the ladder is provided, when the pointed ends 12 of the extension 11 are 80 placed against the building.

The device is capable of many uses which will suggest themselves readily to the operator. In Figure 3, the numeral 16 denotes 85 a roof carrying an eaves trough 17. Assuming that it is not desired to have the ladder 18 press against the eaves trough 17, the extensions 11 may be caused to bear against the roof 16, as shown. The extensions 11 may be removed if desired, and the arms 10 90 may be permitted to bear against the side wall 19 of a building, as shown in Figure 4, the ladder 20 being then located beneath the overhanging cornice 22 and the operator 95 being so placed that when he is on the ladder 20, he can work upon the wall 19 or upon the under surface of the cornice 22. From the arm 10 a paint pot 21 or the like may be suspended, as shown in Figure 4.

100 What is claimed is:

A ladder prop comprising a main member, provided at its inner end with an extension disposed at right angles to said member, the extension being provided with an inwardly extended jaw adapted to engage one edge 105 of a ladder stile, and a second inwardly projecting jaw, adapted to engage the opposite edge of a ladder stile, the second jaw being mounted on the main member, the jaws being spaced apart transversely to cause them 110

to engage the respective edges of a ladder stile at different elevations, the inner ends of the jaws being spaced apart in the direction of the length of the jaws, to clear a ladder rung when the device is adjusted longitudinally of a ladder stile.

In testimony that I claim the foregoing

as my own, I have hereto affixed my signature in the presence of two witnesses.

WILLIAM MATT HEUN.

Witnesses:

FRED BENDERUP,
E. H. MILES.
